US0D1069083S

(12) **United States Design Patent** (10) Patent No.: **US D1,069,083 S**
(45) Date of Patent: ** Apr. 1, 2025

(54) **CLIP ON FAN**

(71) Applicant: **Bei Zou**, Shenzhen (CN)

(72) Inventor: **Bei Zou**, Shenzhen (CN)

(**) Term: **15 Years**

(21) Appl. No.: **29/908,988**

(22) Filed: **Jan. 16, 2024**

(51) LOC (15) Cl. **23-04**

(52) U.S. Cl.

USPC **D23/370**

(58) **Field of Classification Search**

USPC D23/332, 355, 370, 381

CPC F04D 25/105

CLAIM

The ornamental design for a clip on fan, as shown and described.

DESCRIPTION

FIG. 1 is a front, top and right side perspective view of a clip on fan, showing my new design;

FIG. 2 is a rear, bottom and left side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The broken lines shown in the drawings illustrate portions of the clip on fan that form no part of the claimed design.

1 Claim, 8 Drawing Sheets
